ROTARY REDUCING MACHINE

Walter J. Armstrong, Columbus, Ohio, assignor
to The Jeffrey Manufacturing Company, a cor-
poration of Ohio

Application January 28, 1932, Serial No. 589,492

18 Claims.

(Cl. 83—11)

The present invention relates to rotary reducing machines of the swing-hammer type where-
in centrifugally projected hammers or beaters
cooperate with suitable means for the pulveriza-
tion, crushing or shredding of various materials.

The action of the machines of the type above
mentioned depends largely on the size of the
hammers used and the speed at which the rotor
is rotated. In a given machine it naturally fol-
lows that the faster the rotor is rotated the
greater is the centrifugal force of the hammers
and the less their tendency to yield upon impact
with the material to be reduced. Substantially
the same result, as regards yielding under im-
pact, can be secured by utilizing heavier hammers
with the rotor rotating at a reduced speed.

While the application of the present invention
is not limited to any particular type of swing
hammer machine, I shall describe it in connec-
tion with a machine of the type generally con-
templated in United States Patent 1,761,083, is-
sued June 3, 1930 to William K. Liggett. Accord-
ing to the disclosure of this patent the outward
projection of the hammers under centrifugal
force is limited by abutment means on the rotor,
the hammers being so disposed that upon en-
countering unpulverable objects they may recede
entirely within the peripheral outlines of the
main rotor body which comprises essentially a
series of circular discs mounted on a drive shaft.

The basic idea disclosed in the patented ap-
paratus has been further developed by Nils D.
Levin as disclosed in his United States patent
application Serial No. 362,951 filed May 14, 1929.
According to this application, the weight of the
hammers and their length are considerably in-
creased so that whereas the Liggett machine is
essentially a high speed machine, the Levin ma-
chine is intended for operation at lower speeds,
the hammers due to their weight and disposition
being effectively maintained in centrifugally pro-
jected relation.

The present invention is favorably applicable
to a machine of the Levin type, particularly
where a relatively small machine is involved, or
where for any reason the length of the hammers
must be reduced. According to the invention, one
or more of the hammers is so connected with an-
other centrifugally projectible member, which
is preferably another hammer, that the centrifug-
al force of the latter is added to that of the
former so as to aid in sustaining the hammer in
centrifugally projected position against counter-
acting forces arising through impact upon the
material to be reduced. For example, consider-
ing two hammers or beaters to be rigidly inter-
connected, an impact on one of them must react
on both so that the backward swing of the im-
pacting hammer is considerably reduced since

the inertia of the connected hammer must also
be overcome.

While various arrangements are possible, I
have shown two preferred embodiments of the
invention in the accompanying drawing.

In the drawing:

Figure 1 is a vertical section of a machine em-
bodying the invention.

Figure 2 is a plan view of the rotor shown in
Figure 1, and

Figure 3 is a plan view of a rotor embodying a
modified form of beater arrangement.

Referring to the drawing, and first of all to
Figures 1 and 2, reference numeral 10 designates
generally a suitable form of casing or housing 15
and 11 a rotor body of suitable construction.
Since the illustrated casing is well known in the
art and is particularly described in Reissue Pat-
ent 17,334, William K. Liggett, June 25, 1929, its
particular description here is believed to be un- 20
necessary.

The rotor body 11 comprises a number of discs
12 keyed on a shaft 13 which is revoluble in suit-
able bearings of the casing, the discs being sep-
arated by means of spacing collars as at 14 keyed 25
with the discs to the shaft. The disc margins
are provided with a number of apertures all of
which preferably have their centers on the cir-
cumference of a common circle concentric with
shaft 13, the apertures receiving pivot rods 15 30
and abutment rods 16, the ends of the rods pro-
jecting through aligned apertures in end discs
17 and 18 and, as here shown, having nuts
threaded on their ends. As here shown, the rods
15 are spaced 90° from each other and the rods 35
16 are similarly spaced.

Hammers or beaters 19 are pivoted on the pivot
rods 15 in selected ones of the disc spaces. As
shown in Figure 2, for example, alternate disc
spaces are occupied by beaters on each pivot rod,
the beaters of each series being staggered relative 40
to the beaters of the adjacent series. Each
axial series is shown as being composed of three
beaters, although of course the particular num-
ber of beaters is immaterial to the invention.

Each beater 19 comprises a boss portion 20 of
substantially the same width as the rod portions
between the discs and perforated to receive the
associated rod. Each beater also comprises an
elongated shank or arm portion 21 at the free
end of which is an angularly extending relatively
heavy head 22. The width of the arm and main
head portions is less than that of the boss por-
tion in order to permit free oscillation of the
beaters between the discs. In order to prevent 50
chattering, however, the beater heads are pro-
vided with lateral ribs 23 so as to give the heads
a maximum width equal to the width of the
bosses, the faces of the ribs thus being in guided
relation to the discs. Further, each beater is 55
60

provided at its head end with an aperture adapted to receive a tie rod 24.

As shown in Figure 2, the tie rods 24 are substantially equal in length to the pivot and abutment rods 15 and 16 and each is engaged in the head apertures of all of the beaters of a longitudinal series so as to hold the beaters of each series in substantially parallel relation, the tie rods being parallel to the rotor axis as are also rods 15 and 16. In order to afford a proper swinging range for the beaters, the tie rods are passed through sufficiently large disc apertures 25, these apertures as here shown being in the form of slots arcuate on the centers of the pivot rods and of a width slightly greater than the diameter of the tie rods. Beyond the end discs 17 and 18, the tie rods are shouldered and have threaded extremities on which nuts are engaged to prevent longitudinal displacement of the tie rods, the nuts abutting the shoulders so as to avoid clamping action on the end discs.

As shown in Figure 1 the hammers may move from a centrifugally projected material engaging position wherein the arms abut rods 16 to an intermediate inner position wherein the heads lie entirely within the disc edges in abutment with collars 14. If desired, however, the abutment rods and abutment collars 14, as such, may be omitted and the tie rods may cooperate with the ends of the slots as abutment means for limiting the beater swing.

It will be evident that reaction to an impact by one of the hammers of an axial series will be communicated through the tie rods to the other hammers of the series so that the reaction is resisted by the inertia of the entire series of hammers.

According to Figure 3, each longitudinal series of hammers comprises two groups of two hammers, each group being connected by a tie rod 26. The two groups thus act independently of each other, but the hammers of each group act in conjunction, as above described. Obviously, in larger rotors the number of hammers in a group may be increased.

As shown in Figure 1, four axial series of hammers are provided. Due to the described spacing of the series of rods 15 and 16, it will be evident that opposite ones of each series of rods may be removed if a rotor having only two axial series is desired.

It is to be understood that the general combination shown and described as well as the form of the hammers and their arrangement are to be taken only as illustrative of the invention, the scope of which is determined in the following claims.

I claim:

1. In a rotary reducing machine, a rotor, said rotor comprising a beater pivoted thereto to be centrifugally projected upon rotor rotation, another centrifugally projectible member pivoted to said rotor, said beater and member being separate unitary bodies and means connecting said member and beater whereby the centrifugal force of the member is added to that of the beater to assist in sustaining the latter in projected position, said connecting means being remote from the working face of the beater so as not to obstruct the action thereof.

2. In a rotary reducing machine a rotor comprising a beater pivoted thereto on an axis parallel to the rotor axis to be centrifugally projected upon rotor rotation, another centrifugally projectible member pivoted to the rotor on said beater axis,

said beater and member being separate unitary bodies and means connecting said member and beater whereby the centrifugal force of the member is added to that of the beater to assist in sustaining the latter in projected position, said connecting means being remote from the working face of the beater so as not to obstruct the action thereof. 5

3. In a rotary reducing machine, a rotor comprising a beater pivoted thereto on an axis parallel to the rotor axis to be centrifugally projected upon rotor rotation, another centrifugally projectible member pivoted to the rotor on said beater axis, said beater and member being separate unitary bodies and means rigidly connecting 15 said member with said beater at a point removed from the pivotal axis of the latter whereby the centrifugal force of the member is added to that of the beater to assist in sustaining the latter in projected position, said connecting means being 20 remote from the working face of the beater so as not to obstruct the action thereof.

4. In a rotary reducing machine, a rotor comprising a beater pivoted thereto on an axis parallel to the rotor axis to be centrifugally projected 25 upon rotor rotation, another centrifugally projectible member pivoted to the rotor on said beater axis, a radial wall of the rotor separating said member and beater and provided with an aperture, and means connecting said member and 30 beater through said aperture whereby the centrifugal force of the member is added to that of the beater to assist in sustaining the latter in projected position.

5. In a rotary reducing machine, a rotor, said 35 rotor comprising a plurality of separate unitary beaters pivoted thereto to be centrifugally projected upon rotor rotation, and means connecting said beaters whereby the centrifugal force of each is added to that of the other for their mutual 40 sustention in projected position, said connecting means being remote from the working faces of the beaters so as not to obstruct the action thereof.

6. In a rotary reducing machine, a rotor, said 45 rotor comprising a plurality of separate unitary beaters pivotal on an axis parallel to the rotor axis and centrifugally projectible upon rotor rotation, and means connecting said beaters whereby the centrifugal force of each is added to that of the other for their mutual sustention in 50 projected position, said connecting means being remote from the working faces of the beaters so as not to obstruct the action thereof.

7. In a rotary reducing machine, a rotor, said 55 rotor comprising a plurality of separate unitary beaters pivotal on an axis parallel to the rotor axis and centrifugally projectible upon rotor rotation, and means rigidly connecting the beaters at points removed from their axis whereby the centrifugal force of each is added to that of the 60 other for their mutual sustention in projected position, said connecting means being remote from the working faces of the beaters so as not to obstruct the action thereof.

8. In a rotary reducing machine, a rotor, said 65 rotor comprising a series of separate unitary beaters spaced axially thereof and pivotal on an axis parallel to the rotor axis, said beaters being centrifugally projectible upon rotor rotation, and means connecting said beaters whereby the 70 centrifugal force of each is added to that of the others for their mutual sustention in projected position, said connecting means being remote from the working faces of the beaters so as not to obstruct the action thereof.

9. In a rotary reducing machine, a rotor, said rotor comprising a series of separate unitary beaters spaced axially thereof and pivotal on an axis parallel to the rotor axis and provided with aligned apertures, outwardly of said axis and inwardly of the free ends of the beaters so as not to obstruct the beater action, said beaters being centrifugally projectible upon rotor rotation, and a rigid bar passed through said apertures whereby the centrifugal force of each beater is added to that of the others for their mutual sustention in projected position. 5
10. In a rotary reducing machine, a rotor, said rotor comprising a plurality of plates spaced longitudinally of the rotor axis, a plurality of beaters mounted between said plates for pivotal movement about an axis parallel to the rotor axis, said plates being provided with aligned apertures removed from the pivotal axis of the beaters, and a rod connecting the beaters and passed through the plate apertures, said apertures being of a size relative to the rod to afford a suitable range of swing for the beaters, the rod maintaining the beaters always in substantially parallel relation to each other. 15
11. In a rotary reducing machine, a rotor, said rotor comprising a plurality of plates spaced longitudinally of the rotor axis, a plurality of beaters mounted between said plates for pivotal movement about an axis parallel to the rotor axis, said plates being provided with aligned apertures removed from the pivotal axis of the beaters, and a rod connecting the beaters and passed through the plate apertures, said apertures being of a size relative to the rod to afford a suitable range of swing for the beaters, the rod maintaining the beaters always in substantially parallel relation to each other and being adapted to abut ends of the apertures to limit the beater swing. 20
12. In a rotary reducing machine, a rotor, said rotor comprising a plurality of plates spaced longitudinally of the rotor axis, a plurality of beaters mounted between said plates for pivotal movement about an axis parallel to the rotor axis, said plates being provided with aligned apertures removed from the pivotal axis of the beaters, a rod connecting the beaters and passed through the plate apertures, said apertures being of a size relative to the rod to afford a suitable range of swing for the beaters, the rod maintaining the beaters always in substantially parallel relation to each other, and means presented by the rotor for engaging the beaters to limit their swing. 25
13. In a rotary reducing machine, a rotor, said rotor comprising a plurality of beaters pivoted thereto on an axis parallel to the rotor axis, said beaters each comprising an elongated arm portion and an angular head portion, the head portions being centrifugally projected to a material engaging position upon rotor rotation and being movable inwardly of the rotor to an ineffective position upon cessation or counteraction of centrifugal force, means on the rotor limiting the swing of the beaters, and a rod rigidly engaged with the beater heads to maintain the same always in substantially parallel relation to each other. 30
14. In a rotary reducing machine, a rotor, said rotor comprising a plurality of beaters pivoted thereto on an axis parallel to the rotor axis, said beaters each comprising an elongated arm portion and an angular head portion, the head portions being centrifugally projected to a material engaging position upon rotor rotation and being movable inwardly of the rotor to an ineffective position upon cessation or counteraction of centrifugal force, means on the rotor limiting the swing of the beaters, and a rod rigidly engaged with the beater heads to maintain the same always in substantially parallel relation to each other. 35
15. In a rotary reducing machine, a rotor comprising an axially extending series of separate unitary beaters pivotal about a common axis parallel to the rotor axis, said beaters being centrifugally projectible upon rotor rotation, and means remote from the working faces of the beaters and unobstructing to the action thereof tying the beaters together in groups of at least two beaters whereby each beater of a group has enforced participation in the movements of the other beater of that group, the centrifugal force of the beaters of each group being cumulative for their mutual sustention in projected position. 40
16. In a rotary reducing machine, a rotor comprising a rotor body and a plurality of separate unitary beaters pivotal about a common axis parallel to the rotor axis and within the peripheral outlines of said rotor body, said beaters being centrifugally projectible upon rotor rotation, and means positioned within the outlines of the rotor body when the beaters are in projected relation and connecting the beaters together whereby each beater has enforced participation in the movements of the other, the centrifugal force of the connected beaters being cumulative for their mutual sustention in projected position. 45
17. In a rotary reducing machine, a rotor comprising a rotor body and a plurality of beaters pivotal about a common axis parallel to the rotor axis and within the peripheral outlines of said rotor body, said beaters each comprising an elongated arm portion and an angular head portion, the head portions being centrifugally projectible to a material engaging position upon rotor rotation and being movable inwardly of the rotor to an ineffective position, means on the rotor limiting the swing of the beaters, and a rod rigidly engaged with the beaters and positioned to be within the outlines of the rotor body when the hammers are fully projected, said rod tying the beaters together so that each has enforced participation in the movements of the other. 50
18. In a rotary reducing machine, a rotor comprising a rotor body and a plurality of separate unitary axially spaced beaters swingable about a common axis parallel to the rotor axis and within the peripheral outlines of said rotor body, said beaters being centrifugally projectible upon rotor rotation, and means positioned within the outlines of the rotor body at all times and connecting the beaters together so that the centrifugal force of each assists in sustaining the other against inward movement as the result of impact upon material in the machine, each of said beaters having enforced participation in the inward swinging movement of the other during operation of the machine, the beaters being so mounted that their direction of inward swing about their axis is opposite to the direction of rotation of the rotor about its axis. 55
